UNITED STATES PATENT OFFICE.

WILLIAM J. SCHATZ, OF PHILADELPHIA, PENNSYLVANIA, ASSIGNOR TO A. G. SPALDING & BROS. MANF'G CO., A CORPORATION OF MASSACHUSETTS.

CONFORMATEUR OR APPARATUS FOR MAKING CHARTS OF SURFACE CONFORMATIONS.

1,206,144.

Specification of Letters Patent. Patented Nov. 28, 1916.

Application filed December 22, 1915. Serial No. 68,255.

To all whom it may concern:

Be it known that I, WILLIAM J. SCHATZ, citizen of the United States, residing at Philadelphia, Pennsylvania, have invented 5 certain new and useful Improvements in Conformateurs or Apparatus for Making Charts of Surface Conformations, of which the following is a specification.

My invention is designed for use of physical directors or physicians for obtaining 10 charts of the conformation of parts of the bodies of subjects or patients, so that the progress resulting from corrective exercises may be ascertained and viewed by comparing 15 a chart made at one time with a chart made at a later date after the subject or patient has been put through an exercise, or course of exercises, for the purpose of developing certain muscles, and correcting any 20 abnormal parts of the physical structure.

The invention consists in the features and combination and arrangement of parts hereinafter described and particularly defined by the appended claims.

25 In the drawings Figure 1 illustrates the use of the appliance for making anterior-posterior curves; Fig. 2 illustrates the use of the apparatus for making charts of lateral curves of the spine; Fig. 3 illustrates the use 30 of the apparatus for making charts of transverse curves of the back; Fig. 4 is a front view of the apparatus in condensed form, parts being broken away, to economize space; Fig. 5 is a side view of the apparatus 35 of Fig. 4; Fig. 6 is a top view of the apparatus of Figs. 4 and 5; Fig. 6^a is a top view of a detail. Fig. 7 shows, in elevation and edge view, a special form of roller contact; Fig. 8 shows similar views of another form 40 of roller contact.

The apparatus is adapted to be attached to the wall, door jamb, or a door, and while it may assume various forms, in the particular construction illustrated it comprises 45 essentially a suitable vertically disposed bar or track 1 which is supported by upper and lower brackets 2, 3. These brackets consist of a fitting 4 to receive the upper and lower ends of the bar 1, a pin or rod 5, and a wall 50 piece or support 6, the said pin being held in sockets in the parts 4 and 6 by finger screws 7 and 8. The pins 5 may be of any desired length, according to the requirements of the position at which the apparatus is mounted.

If upon a flat wall, the pins 5 may be of 55 considerable length, so that the track or bar 1 will stand out the proper distance from the wall in order to give room for the patient or subject to assume different positions in relation to the apparatus for making 60 various kinds of charts. The track or rod 1 has slidably connected therewith a frame or plate 9 having upper and lower collars or bosses 10, 11, embracing the rod 1, and adapted to slide thereon. This plate carries 65 a pair of parallel rods 12, and the connection between these rods and the plate is of universal character, consisting of a forked coupling 13 at the lower end of the rod 12, said forked coupling being pivotally mounted to 70 a member 14 by the pins or screws 15, 16, passing through the ends of the fork, and into the piece 14, the said pins or screws having plain portions at 17 on which the fork may turn. The piece 14 is in the form of a 75 sleeve through which passes a pin 18 having a plain portion at 19 upon which the sleeve 14 may turn, the said pin 18 having a screw threaded reduced end 20 passing through a boss 21 on the plate or carrier 9, a nut 22 on 80 the screw-threaded extension of the pin 18 serving to hold the pin in place on the carrier 9. The pin 18 has a kerfed head 23, to receive a screw driver for turning the pin or for holding it while the nut is set in place. 85 This universal coupling just described is used at the lower end of each of the parallel rods 12, and it will be seen that these rods can swing forwardly and backwardly, or in other words, toward and from the wall or 90 other support upon which the appliance is mounted, or the parallel rods may be swung laterally in relation to the upright support or track 1. At their upper ends the rods 12 carry a cross rod 24 by swivel joints consisting of sleeves 25 at the upper ends of the rods 12, which sleeves have pins 26 passing through them which carry, at their outer ends, bosses or sleeves 27 through which the cross rod 24 extends, this cross rod 24, it 95 being observed, carrying at one end a pencil 28, and at its other end a stylus or other suitable contact to move over the surface of the body of the subject or patient. The sleeves 27 are fixed to the rod 24 by the set 100 screw 29, and as the parallel rods swing to one side or the other, the pins 26 of the sleeves 27 will turn in the heads or sleeves 25

fixed to the upper ends of the rods 12, and thus the horizontal position of the tracing rod 24 may be maintained.

The upper ends of the parallel rods 12 are held in proper relation by a cross piece 30 extending from one pin 26 to the other, the said pins passing through this cross rod, and being held by cotter pins 31 and washers 32. The contact member which is to engage the body of the patient may be either a roller, as shown at 33, or a stylus, as shown at 34. Both of these parts are carried by a bracket 35 which may be set in different positions on the end of the tracing rod to meet the different conditions under which the appliance may be used. For this purpose the bracket 35 is provided with a longitudinal opening 36, and when the bracket is on the tracing rod with the rod engaging this opening it is fixed by the set screw 37. The bracket 35 may be set at right angles to the tracing rod by utilizing the opening 39 and the set screw 40, so that the stylus 34 will then extend in a direction at right angles to the tracing rod 24, or the roller 33 may be positioned with its axis parallel to said rod instead of transversely thereto, as shown in Figs. 4, 5 and 6. The stylus may be adjusted into either a position of use beyond the plane of the periphery of the roll 33, or to a position out of use in rear of the said roller 33, and for this purpose the stylus passes through bearings 41, 42, projecting laterally from the bracket 35, and a set screw 43 is provided to set the stylus in any desired position.

The contact roller 33 is removably mounted in the forks 35^a of the bracket 35, and by swinging a catch lever 45 on its pivot 46 the pivot pin 47 of the roller may be removed and the roller withdrawn, and either the roller of Fig. 7 may be substituted or that of Fig. 8. The bracket 35 has a third opening 39^x which lies at a quarter turn from the opening 39, and this enables the operator to place the bracket at right angles to the tracing rod 34, but at a quarter turn in relation to the position permitted by the opening 39. With the bracket held on the tracing rod by the opening 39^x and its set screw 37, either the roller or the stylus may be placed in service as in Fig. 2 to get a tracing of lateral curvatures with either the stylus or the roller, the roller being turnable about a horizontal axis, but with the bracket held on the tracing rod by the opening 39 and its set screw the roller 33 would travel with its axis at right angles to the axis of the tracing rod. With this disposition of the parts the roller can be used for making charts of the transverse contour of the back. Briefly stated, the bracket has openings to provide for three positions of the bracket 35. One with the bracket in line with the tracing rod, and the other two to arrange

the bracket at right angles to the tracing rod, and in two different right angular positions.

Fig. 1 shows the position of the apparatus and of the subject in taking anterior-posterior curves, the bracket 35 being adjusted to set in line with the tracing rod, and the roller 33 being in use. The pencil 28 is bearing on the chart, and the operator is omitted from this view. The subject's position is determined by a suitable support 50 having rests 51 for the arms. The subject, by resting his body against this support and by allowing his arms to bear on the cross bar, can maintain a natural attitude without the use of clamps, straps, or other objectionable devices which tend to make the subject assume an unnatural position. For charts to show progress of chest raising exercises the patient or subject would be positioned a half turn from the position shown in Fig. 1. In getting a chart as shown in Fig. 1, the carrier 9 would be moved vertically of the rod or track 1 to make the stylus or roller traverse the middle or other line of the back, the tracing rod moving lengthwise as the thoracic and lumbar regions are traversed, this lengthwise movement being permitted by the swinging of the parallel bars about the pivot pins 18.

In Fig. 2 the subject is in position for the tracing of lateral curvature of the spine, the roller or stylus in this case following the spine from its upper to its lower end as the carrier 9 is allowed to move down along the rod 1. The making of charts for lateral curvatures is rendered more complex than such curves as anterior-posterior above mentioned, because we have to deal also with the anterior-posterior curves as well as the lateral curves, for instance, of the spine, giving rise to a movement of the tracing rod to and from the plane in which the chart lies. To meet this difficulty, the stylus may be held loosely in the bracket 35 so as to slide in the bracket, and then the operator, by using one hand to guide the tracing rod and keep it substantially parallel with the face of the chart as it moves downwardly and with the pencil on the chart, can, with his other hand, keep the stylus pressed against the subject, the stylus being moved in or out as the anterior-posterior curves may demand, and thus eliminate the influence that these curves would otherwise have on the tracing by reason of said rod assuming different positions in relation to the surface of the chart.

Fig. 3 illustrates the position of the subject, operator, and the apparatus in making a tracing of the transverse line of the back, the bracket 35 being adjusted to extend at right angles to the tracing rod. The operator can exert control over the tracing rod by taking hold thereof with both hands near

the ends of said rod, and he can control the vertical movement of the tracing rod and parallel rods 12. This transverse curve will show any inequalities between the right and left portions of the back.

In Figs. 1 and 3 the apparatus is shown as attached to the frame of a closet door, thereby giving room for the subject to assume different positions. In Fig. 2 the apparatus is shown as attached to the wall near a corner or shoulder thereof, so that the subject may assume all necessary positions. The apparatus may be attached to a door which, being swung back, will enable the subject to be properly positioned for any desired tracing, and the door may be held by any suitable form of catch mechanism. Instead of the roller 33 as a tracing implement having a convex periphery, the roller shown in Fig. 7 may be employed having a concave periphery, and this may be used for tracing along the spine, or a small roller, such as Fig. 8, may be employed.

I claim as my invention:—

1. In combination in apparatus for making tracings or curves of the human body, a chart disposed in a vertical plane, a horizontally disposed tracing rod having marking means at one end to engage said chart and a tracing device at the other end to bear upon the body and follow its curves, a vertically movable support for said rod, and connecting means between said support and said rod to permit the same to have movement longitudinally and vertically while maintaining the same in horizontal position, substantially as described.

2. In combination in apparatus of the class described, a horizontal tracing rod having marking means at one end and a rotary member at its other end having a grooved periphery to follow the curve or surface to be traced, a vertically movable carrier, and parallel rods connecting the tracing rod with the vertically movable carrier, and having pivotal connection with said carrier and with said horizontal tracing rod, substantially as described.

3. In combination in apparatus for making tracings or curves of the human body, a vertically arranged chart, a vertically arranged support, a horizontally disposed tracing rod, a vertically movable carrier on the vertical rod, a connection between said carrier and the horizontally disposed rod to permit said rod to have longitudinal and lateral movement while maintaining the same in horizontal position, marking means at one end of the tracing rod to engage said chart and a tracing implement at the other end of the rod, said tracing implement being adjustable to be set on said horizontal rod to work on a surface lying in a plane transverse to the end of said rod, whereby said rod will move longitudinally as it is raised

and lowered along the irregularities of said surface or to be set on said rod to work on a surface lying in a plane substantially parallel with the rod, whereby said rod will be caused to assume different elevations as the rod is moved longitudinally, substantially as described.

4. In combination in apparatus of the class described, a tracing rod, a movable support therefor, permitting said rod to have both longitudinal and lateral movement, marking means at one end of the rod and a tracing implement at the other end of the rod, said tracing implement being adjustable to operate parallel to the axis of the tracing rod or at right angles thereto, substantially as described.

5. In combination in apparatus of the class described, a tracing rod, a movable support therefor, marking means at one end of the rod and a tracing implement at the other end of the rod, said tracing implement consisting of a bracket having openings at right angles to each other to receive the tracing rod for setting the implement in different positions relative to the said rod, said tracing rod having movement both longitudinally and laterally, substantially as described.

6. In combination in apparatus of the class described, a tracing rod, a movable support therefor, marking means at one end of the rod and a tracing implement at the other end of the rod, said tracing implement comprising a bracket, a roller and a stylus supported thereby with means for holding the stylus and roller relatively adjustable upon said bracket, substantially as described.

7. In combination in an apparatus of the class described, a tracing rod, a movable support therefor; marking means at one end of the rod and a tracing implement at the other end of the rod, said implement comprising a bracket having a fork, a roller in said fork, bearings projecting laterally from the bracket, a tracing rod adjustably mounted in said bearings, a longitudinal socket in the bracket to receive the tracing rod, said socket being parallel with the stylus and openings extending transversely through the bracket, substantially as described.

8. In combination in apparatus of the class described, a tracing rod, a movable support therefor, marking means at one end of the rod and a tracing implement at the other end of the rod, said implement comprising a bracket with an opening extending lengthwise thereof to receive the tracing rod and with two openings extending at right angles to each other and to the longitudinal opening, and a contact member carried by the said bracket, substantially as described.

9. In combination in apparatus of the class described, a tracing rod, a movable

support therefor, permitting said rod to move both longitudinally and laterally, marking means at one end of the rod, and a rotary tracing implement at the other end of the rod with means for adjustably holding said tracing implement with its axis parallel with that of the rod, or at right angles thereto, substantially as described.

10. In combination in apparatus of the class described, a tracing rod, a movable support therefor, permitting said rod to move both longitudinally and laterally, marking means at one end of the rod, and a tracing implement at the other end of the rod with means for adjustably holding said tracing implement to move said rod longitudinally or for holding said implement at right angles to the rod in either one of a plurality of said right angular positions, substantially as described.

11. In combination in an apparatus for making tracings or curves of the human body, a chart disposed in a vertical plane, a horizontally disposed tracing rod having marking means at one end to engage said chart and a tracing device at the other end to bear upon the body and follow its curves, a vertically movable support for said horizontal tracing rod and connecting means

between said support and said rod to permit the same to have movement longitudinally, vertically and sidewise while maintaining said rod in its horizontal position, substantially as described.

12. In combination in an apparatus for making tracings or curves of the human body, a vertically arranged chart, a vertically arranged support, a horizontally disposed tracing rod, a vertically movable carrier on the vertical rod, a connection between said carrier and a horizontally disposed rod to permit said rod to have longitudinal and lateral movement while maintaining the same in horizontal position, marking means at one end of the tracing rod to engage said chart and a tracing implement at the other end of the said rod, said tracing implement being adjustable to occupy a position vertical and transverse to the rod and also a horizontal position transverse to said rod, substantially as described.

In testimony whereof, I affix my signature in presence of two witnesses.

WILLIAM J. SCHATZ.
